AIR FEED AND VENT FOR CLOSED TOP GAS STOVES

Original Filed May 11, 1925

INVENTOR.

Joseph B. Gardner

Patented Feb. 19, 1929.

1,702,297

UNITED STATES PATENT OFFICE.

JOSEPH B. GARDNER, OF OAKLAND, CALIFORNIA, ASSIGNOR TO HAMMER-BRAY COMPANY, OF OAKLAND, CALIFORNIA, A CORPORATION OF CALIFORNIA.

AIR FEED AND VENT FOR CLOSED-TOP GAS STOVES.

Original application filed May 11, 1925, Serial No. 29,365. Divided and this application filed February 3, 1926. Serial No. 85,668.

The invention relates to means incorporated with a burner chamber of a closed top gas stove, for insuring an adequate supply of fresh air to all of the burners in the chamber. This application forms a division of my original application Serial No. 29,365, which was filed in the Patent Office on May 11, 1925, the present application relating more particularly to the embodiment of the invention illustrated in Figures 3 and 4 of said original application.

Most gas stoves, particularly ranges, are equipped with front and rear gas burners which are positioned in what may be termed a burner chamber. Where a grate has been superposed over the burners to provide a cooking top, no difficulty has been experienced in the matter of an adequate external supply of fresh air at the burners. However, when the burner chamber has been covered with a closed or solid top, it has been found that the rear burners receive less fresh air for combustion than do the front burners, since the burner compartment is usually open only at the front and such fresh air that flows by the front burners escapes into the flue vent at the rear of the chamber, without the desired contact with the rear burners. Various attempts have been made to remedy these difficulties, but in general the results obtained thereby have not been satisfactory. The reason I believe lies in the fact that too little attention was given to the effect of the location of the burnt gas discharge opening or openings upon the flow of the fresh air in the chamber. Furthermore, the structures involved in such attempts in most instances require forming the bottom and top plate in such manner as to necessitate the use of a special drip-pan and render the complete removal of such top plate impractical. In accordance with the foregoing it is my object to insure adequate supply of fresh air to all the burners in the chamber without entailing the objectional features referred to.

The invention possesses other objects and features of advantage, some of which, with the foregoing, will be set forth in the following description of the preferred forms of my invention which are illustrated in the drawings accompanying and forming part of the specification. It is to be understood that I

do not limit myself to the showing made by the said drawings and description, as I may adopt variations of the preferred forms within the scope of my invention as set forth in the claims.

Referring to said drawings: Figure 1 is a perspective view of the cooking top portion of a stove embodying my invention.

Figure 2 is a vertical section of the stove portion, illustrated in Figure 1 and taken on the line 2—2 thereof.

Figure 3 is a perspective view similar to Figure 1, illustrating another embodiment of the invention.

Figure 4 is a vertical section taken on the line 4—4 of Figure 3.

Briefly expressed, my invention comprises, providing a fresh air inlet at the rear as well as at the front of the chamber, and further providing a passage directly into the central portion of the chamber from either such rear inlet or the vent for the combustion products so that upon the discharge of the combustion products into the vent, the air entering from the rear inlet will be caused to move toward the center of the chamber and consequently against the rear burners, in substantially the same manner as the air entering from the front inlet is caused to be directed against the front burners.

In the drawings, as previously noted, there are illustrated two embodiments of the invention. One embodiment utilizes a passage from the vent to cause the air to flow toward the central portion of the chamber whereas the other embodiment utilizes for such purpose a passage from the rear fresh-air inlet.

In Figures 1 and 2, in which are illustrated the first mentioned embodiment, the stove 4 is provided with a closed gas-cooking-top 6 which includes a top-gas-burner compartment 7 whose sides are defined by walls 8 and 9 and a rear wall 12. The bottom of the compartment is preferably defined by a plate 13 while the top is closed by the cooking plate 14 here shown as a section of the top member 15 which also overlies and forms the cooking plate for the fire-box 16 at one side of the chamber. The cooking plate or section 14 is made removable from the top member 15 so that if desired a grate (not shown) may be

substituted therefor. Openings 17 are provided in the plate 14 and are normally covered by lids 18. The compartment 7 is formed rather shallow in order that a maximum space may be available thereunder for other uses. Arranged in the compartment are front and rear top-gas-burners 19 and 21 which are preferably aligned with the openings 17 of the cooking plate.

10 A proper gas mixture for the burners is arranged to be supplied thereto through pipes 22 provided with air mixers 23 and connected to a gas manifold 24 at the front of the stove. In most types of closed top gas stoves at least 15 part of the fresh air for completing combustion at the burners is arranged to enter directly into the compartment through the opening or space 25 extending across the bottom portion of the front plate 26 thereof and 20 the products of combustion are arranged to discharge directly into a vent located at the rear of the compartment. Such location of the vent with respect to the fresh air inlet, while affording a proper supply of fresh air 25 to the front-burners, causes the air vitiated at the front burners to be drawn over the rear burners and thus hinder complete combustion thereat. It will be understood since other 30 stove units, such as the fire-box and ovens 27 and 28 here shown, are usually positioned at one or both of the sides of the compartment, additional fresh air for the rear burners is best brought from the rear of the chamber. It will be clear, however, that any 35 attempt to provide fresh air inlet openings at the rear of the chamber with the vent likewise located, will cause the fresh air from said inlet to be drawn into the vent without materially associating with the rear burners. 40 In accordance with the present invention, I so arrange the intake of the vent that the use of fresh air inlet openings at the rear of the chamber is made fully effective to furnish an adequate supply of fresh air at the rear 45 burners. Accordingly, one or more openings 29 are provided in the rear wall 12 through which fresh air is arranged to be drawn directly into the chamber from without the stove. Registering with a vent opening 31, preferably provided in the wall 12, are internal and external flue portions 32 and 33 respectively. The internal flue portion 32 comprises branches 34 which extend to and along the opposite side walls 8 and 9 of the 50 chamber and have their inlet openings 36 located opposite the space between the adjacent front and rear burners. The openings 36 are disposed in a plane above that of the 55 fresh air inlets at both the front and rear 60 of the chamber, so that the combustion products will move to the flue by convection. It will thus be noted that communication of the flue with the chamber is effected only 65 through the medium of the flue openings 36. It will now be clear that a fresh air supply is

provided for the front and rear burners independently, and that by reason of the location of the flue openings in the chamber, the vitiated air from a front burner will not associate with a rear burner.

70 The flue branches are positioned well toward the top of the chamber 7 so that obstruction of the chamber is avoided and a full-sized drip pan of maximum size may be placed therein. Furthermore, the branches 75 34 are preferably formed separately of the top member 15 to thereby permit the removal of the top section 14.

Another arrangement for preventing the 80 vitiated air from the front burners from circulating over the rear burners, and furnishing the latter with an independent supply of 85 fresh air is shown in Figures 3 and 4. In this arrangement, fresh air for the rear burners is drawn into the chamber through inlet 90 openings 41 formed in the rear wall 12 of the chamber and positioned adjacent the side walls 8 and 9 thereof. The fresh air from such openings is caused to flow in streams 95 inwardly and adjacent the sides of the chamber, and then caused to pass over the rear burners before its discharge from the chamber is permitted. As here shown, passages 42 100 through which the incoming air is directed toward the central portion of the chamber are defined between the bottom 13 and a plate 43, and the side walls of the chamber and partitions 44. The plate 43 is positioned against the rear wall of the chamber and separates the intake openings from the vent opening 46 of the flue, it being noted that the vent opening is positioned above the plate, while the inlet openings and the passages 42 lie below the plate. Since the vent opening 46 is located opposite the space between the rear 105 burners, the vitiated air from the front burners, in flowing to said opening, will, for the most part, pass through said space between the burners. Furthermore, the air from the passages 42, while and after passing over the rear burners, will not only supply the necessary aid to combustion at the latter, but will force the stream of vitiated air from the front burners to still greater confinement in the space between the rear burners. The bottom edges of the partitions 44 are preferably 110 spaced from the bottom 13 of the chamber in order that a drip-pan 30 may extend thereunder.

115 I claim:

120 1. In a stove, a closed top-gas-burner chamber having fresh air inlets adjacent the bottom of different sides thereof and a vent adjacent the top of one of said sides, burners within the chamber adjacent said sides, and a horizontal baffle plate extending across said chamber positioned adjacent said last side and in a plane below the top of said burners and separating the vent and adjacent inlet whereby the fresh air drawn into the chamber 125 130

ber through the latter may be caused to contact intimately with the adjacent burner before it may discharge through the vent.

2. In a stove, a closed top-gas-burner chamber having fresh air inlets adjacent the bottom and opposite side portions thereof, burners in said chamber adjacent said inlets having jet orifices, a flue opening being located in said chamber adjacent the top and one of said side portions, a substantially horizontal baffle plate positioned in a plane below the jet orifices of said burners extending across said chamber at said last side portion and separating said flue opening and the adjacent inlet, whereby the fresh air will be prevented from discharging into said flue opening before entering into intimate contact with the adjacent burner.

3. In a stove, a closed top-gas-burner chamber having fresh air inlets adjacent the bottom of the front and rear thereof, a flue opening at the rear thereof located adjacent the top, a substantially horizontal plate separating the rear portion of the chamber into superposed upper and lower compartments extending the full width of the chamber, said flue opening and adjacent inlet respec-

tively communicating with the upper and lower compartments, a burner in said chamber adjacent the front thereof, and a burner 30 in the chamber lying in a plane above said plate and positioned to intercept the fresh air from the rear inlet before it passes out of the chamber through the flue opening.

4. In a stove, a closed top-gas-burner chamber having fresh air inlets adjacent the bottom of the front and rear sides thereof, a substantially horizontal baffle plate positioned in the rear of said chamber above the inlets thereat and in spaced relation from the 40 top of the chamber, a vent at the rear of the chamber located mediate of the chamber sides and above the plate, said rear inlets being located adjacent the sides of the chamber, burners in the front of the chamber, burners 45 in the rear of the chamber lying at least partially above said plate, and deflecting means on the bottom of said plate arranged to direct the flow of air from each of said rear inlets toward a different rear burner. 50

In testimony whereof, I have hereunto set my hand at Oakland, California, this 29th day of January, 1926.

JOSEPH B. GARDNER.
